[57] **CLAIM**

The ornamental design for a door prop for a refrigerator, as shown and described.

DESCRIPTION

FIG. 1 is an environmental view showing my novel design for door prop for a refrigerator;

FIG. 2 is a top plan view of which the bottom view is a mirror image thereof.

FIG. 3 is a left side end view of which the right side is a mirror image thereof.

FIG. 4 is a front elevational view of the door prop for a refrigerator; and,

FIG. 5 is a rear elevational view thereof.

The broken lines are shown for illustrative purposes only and form no part of the claim design.
